LAUNDRY LOT MARKER

Forrest J. Couch, Cincinnati, Ohio, assignor to
The American Laundry Machinery Company,
Cincinnati, Ohio, a corporation of Ohio

Application March 10, 1932. Serial No. 597,977

4 Claims. (Cl. 68—11)

My invention relates to a lot or bundle marker for flatwork ironing machines and is designed for use particularly in conjunction with a flatwork ironing machine having in connection therewith an automatic bundle assorting device, such, for example, as is shown in my copending application, Serial No. 493,050, filed November 3, 1930. However, the lot or bundle marker is applicable to any ironing machine.

When laundered goods are presented to flatwork ironing machines, each piece is fed to the ironer separately and, to inform the attendant at the delivery end of the machine as to the number of pieces in the customer's lot or bundle, the customer's name or identification mark, and when the last piece of any customer's goods has passed through the machine, a marker of some sort is passed through the ironer immediately after the last piece of that customer's goods is fed through the machine by the feeding operator. Different laundries have different systems and different types of markers. That is, some have cloth or paper markers bearing the operator's name or number and others are identified by a small metal clip secured to a piece of cloth.

The objects of my invention are to provide a lot or bundle marker which is applicable to any present laundry system by providing a marker including pockets or the like for receiving different types of identification means that are used in different laundries; to provide a marker of sufficient stiffness that it will not easily become lost among garments of any texture; to provide a marker of the above type that will retain its desired shape without lapping or folding at its front edges; and to provide a lot or bundle marker having means thereon serving to trip mechanism, as in my previously mentioned copending application, which will automatically cause a receiving receptacle or conveyor section to move away from the delivery end of the ironing machine when the ironer is equipped with an automatic bundle assorting device.

Various other objects and advantageous features of my invention will be seen in the following description and one embodiment thereof may be seen in the accompanying drawings wherein similar characters of reference designate corresponding parts, and wherein:

Fig. 1 is a perspective view of a laundry lot or bundle marker embodying my invention; Fig. 2 is a top plan view of the lot or bundle marker; Fig. 3 is a sectional view of the lot or bundle marker taken on the line 3—3 of Fig. 2; Fig. 4 is a sectional view taken on the line 4—4 of Fig. 2; Fig.

5 is a view showing a lot or bundle assorting mechanism in conjunction with the ironing parts of a flatwork ironer and with which my lot or bundle marker is particularly applicable to use; and Fig. 6 is a side elevation of the operating means for the delivery conveyor forming a part of the mechanism shown in Fig. 5 but with the parts thereof out of operative position.

In Figs. 1—4 of the drawings, I have shown a lot or bundle marker adapted to be used with the flatwork ironing machines of a laundry consisting of a main body portion 1 preferably made up of a single piece of heavy canvas or like material of rectangular shape and approximately twice as long as it is wide and with the two adjacent corners 2 on the front edge thereof, which is first to be fed into an ironing machine, rounded substantially as shown. This rounding of the corners 2 effectively prevents the material from becoming bent over on itself or folded at the corners from constant use and handling which will occur when the corners are left square or nearly so.

As shown, a large open pocket 3 is provided on the body portion of the marker 1 by a piece of heavy canvas or the like 4 securely fastened to the body portion 1 by stitching or otherwise, the piece 4 being only stitched substantially on three sides thereof to leave an open pocket into which lot or bundle identifying means such as a card or the like may be inserted and sent through the ironing machine from the goods feeder to the goods receiver whereby the goods receiver may properly identify the lot or bundle. Means are also provided for effectively holding a lot or bundle identifying means such as a small metal tag 90 or the like, this means consisting of a small pocket 5 formed by stitching or otherwise securing the piece 4 to the main body portion 1 as at 6.

To provide a thickened portion on the lot or bundle marker whereby the lot or bundle marker will be effective to operate a tripping mechanism for causing actuation of an ironed goods receiving conveyor or receptacle, a heavy piece of material 7 such as canvas or the like that is somewhat smaller than the piece 4, particularly in width, is securely fastened to the piece 4 by stitching or otherwise to form a closed pocket that is filled with suitable padding. This padding is preferably sheet material so that it will not become wadded or bunched from continual handling. The thickened portion, as well as the pockets, are preferably located at the rearward edge of the lot or bundle marker, and indicating means such as the arrows 8 may be provided on the lot or bundle marker to advise an operator as to

positioning the lot or bundle marker for travel through the ironing machine or, in other words, which is considered the front edge of the lot or bundle marker.

5 In Figs. 5 and 6 of the drawings, I have shown an assorting and delivery mechanism identical with that shown in my copending application, hereinbefore mentioned, in connection with which the lot or bundle marker is particularly applicable for use. This apparatus is in combination with an ironing roll 9 and ironing chest 10, the roll and chest being of the usual type found in a flatwork machine. Also, as is usual in ironing machines of this type, a tape 11 passes around the ironing roll and between the roll and chest.

10 In the apparatus, bracket 12 is rigidly secured to each side of the rearwardmost end of the chest 10 and each bracket is provided with an upwardly extending ear 13 to which an arm 14 is pivoted as at 15. This arm carries the usual stripper roller 16 intermediate its ends, the stripper roller being mounted on a shaft journalled in the arms. A roller 17 is also carried by the arms 14 and is adapted to be driven by a sprocket chain 18 traveling around a sprocket on the shaft which carries the roller 17 and around a driven sprocket 19. The ironed goods from between the roll and chest passes under the roller 17 and then falls away from the rearwardmost end of the chest 10 or, if necessary, is stripped from the tape 11 by the stripper roller 16.

15 The goods falling away from the rearward end of the chest 10 or being stripped from the tape 11 by the roller 16 fall into successively presented receptacles on a conveyor mechanism, the receptacles being formed by plates 20 hingedly mounted on a conveyor 21 so as to overlap and form receptacles along the upper lap of the conveyor 21 as shown in Fig. 5, the receptacles continuing along the entire length of the upper lap of the conveyor and being successively moved forwardly by actuating mechanism rendered effective by the operation of a trip mechanism which is, in turn, rendered effective by the passage of one 20 of the lot or bundle markers through the ironer as will hereinafter be apparent.

25 The conveyor 21 is driven by a pair of sprockets 22, one of which is shown, and the size of the sprockets is such that the conveyor 21 will travel a distance equal to the distance from one partition to another on the upper lap thereof on each revolution of the sprockets. In order to control the operation of the conveyor 21, a trip 23 is provided that takes the form of a bell crank lever having a long and a short arm, the trip being pivotally mounted as at 24 on a disk 25 which is rigidly mounted on a shaft 26. Loosely mounted on the shaft 26 a short distance from the disk 25 is another constantly and positively driven disk 27 which is provided with four pins or lugs 28 projecting from its face toward the disk 27 and into the same vertical plane as that of the short arm of the trip 23. The trip 23 is limited in its movement about the pivot 24 in one direction by a stop pin 29 and in the other direction by a stop pin 30. A spring 31 normally tends to hold the trip 23 in a position with the long arm thereof against the stop 30 and with the short arm of the trip in a raised position whereby it will be in the circular path of travel of the pins 28.

30 The disk 27 is positively and constantly rotated in a clockwise direction and is loosely mounted on the shaft 26 with the trip 23 on the disk 25, which is rigidly mounted on the shaft 26, in such position that the short arm thereof will not contact

with any of the pins 28 whereby the shaft 26 and sprockets 22 will not be rotated and the conveyor 21 will remain stationary.

35 To provide for the lot or bundle marker to act as a means for moving the trip 23 to such position that the short arm thereof will be raised into the path of the pins 28, an arm 32 is pivotally mounted on the frame of the conveyor and has its free end arranged to be in either of two positions, namely, in the path of the long arm of the trip 23 as shown in Fig. 5 wherein the short arm of the trip 23 will be moved out of the path of travel of the pins 28 and the trip held against the stop 29, or out of the path of the long arm of the trip 23 as shown in Fig. 6 and in such position that the trip will be moved against the stop 30 by the spring 31, which movement will cause the short arm of the trip to be moved upwardly into the path of travel of the pins 28. As shown in the drawings, the free end of the arm 32 is made to swing in a vertical plane out of and into the path of the trip 23 which moves the disk 25 and the free end of the arm 32 is connected by a link 33 to the free extending end of one of the arms 14 hereinbefore described whereby, when such arm 14 is raised, the arm 32 will be raised and its free end lifted out of the path of the long arm of the trip 23 as shown in Fig. 6 to permit the trip to be swung to the position hereinbefore described by means of the spring 31 to thereby bring the short arm of the trip into the circular path of the pins 28 and operatively connect the disks 25 and 27 together. The chain 18 is positioned remotely from the link 33 to not interfere with the raising of the one arm 14 and arm 32.

40 Since the disk 25 and sprockets 22 are rigidly mounted on the shaft 26 and the constantly driven disk 27 is loosely mounted on the shaft 26 with the disks so arranged that they may be operatively interconnected together for movement of the disk 25 and sprockets 22 in one direction by the swinging of the short arm of the trip 23 into position to be engaged by one of the pins 28, it follows that raising of the arm 32 out of the path of the long arm of the trip 23 by the passage of a lot or bundle marker beneath the roller 17 will permit the disks to be operatively connected together and the conveyor moved the distance of one compartment thereon.

45 In the operation of this device, the ironed goods fall from the delivery end of the steam chest 10 into the compartment of the conveyor 21 which is at rest directly below such delivery point and, when the last piece of a customer's goods has been fed into the feed end of the ironing machine, the operator then follows it immediately with the lot or bundle marker herein described which passes through the ironer and under the roller 17 whereby such roller will be lifted when the thickened portion of the lot or bundle marker passes thereunder to cause the extended free end of the arms 14 to which the link 33 is connected to be moved upwardly about the pivot 15 of the arms a sufficient distance to release the trip 23 by moving the arm 32 upwardly and out of engagement therewith as shown in Fig. 6. This raising of the arm 32 will permit the short arm of the trip 23 to move into the path of travel of the pins 28 as hereinbefore described to operatively connect the constantly driven loosely mounted disk 27 with the disk 25 rigidly mounted on the shaft 26. This will cause the shaft 26 and sprockets 22 to be driven through one complete revolution and movement of the filled compartment on the conveyor out of registry with the delivery point of

the ironing chest and the next succeeding compartment into registry therewith, the goods being removed from the compartments to any point in the travel of the compartment along the upper 5 lap of the conveyor.

The thickened portion of the lot or bundle marker is of such width that it will pass entirely out from under the roller 17 prior to the disk 25 and sprockets 22 making one complete revolution 10 whereby the arms 14, link 33, and arm 32 may again move downwardly with the arm 32 positioned to engage the long arm of the trip 23 before the disk 25 travels through a complete revolution whereby the long arm of the trip will engage 15 the free end of the arm 32 and the short arm of the trip 23 will be moved out of the path of the pins 28 by continued movement of the disk 25 which will operatively disconnect the disk 25 from the disk 27.

20 Referring to the drawings and the preceding description, it will be seen that I have provided a lot or bundle marker for ironing machines that is particularly adapted for use with an ironing machine having an automatically operating goods 25 assorter and conveyor in connection therewith. Likewise, it is adapted for use as a signal operating means or the like. The lot or bundle marker embodies the advantageous feature of being provided with means whereby it will act as a carrier 30 for lot or bundle identification means and is of a nature to permit it to be readily located and separated from a lot or bundle of goods as well as being of a nature to retain its desired shape and effectiveness.

35 What I claim is:

1. A lot or bundle marker for use with flatwork ironing machines, said marker comprising pad means adapted to be passed through an ironing machine to indicate when a lot or bundle 40 has been ironed, said pad means including means whereby it may act as a carrier for lot or bundle identifying means from one side of the ironing

machine to the other, and means whereby said pad means will be effective to cause actuation of a lot or bundle assorter and conveying means or the like.

2. A lot or bundle marker for use with flatwork ironing machines, said marker comprising pad means adapted to be passed through an ironing machine to indicate when a lot or bundle has been ironed, said pad means including means whereby it may act as a carrier for lot or bundle identifying means from one side of the ironing machine to the other and having rounded front edge corner portions on the body thereof, and means whereby said pad means will be effective to cause actuation of a lot or bundle assorter and conveying means or the like. 80

3. A lot or bundle marker for use with flatwork ironing machines, said marker comprising pad means adapted to be passed through an ironing machine to indicate when a given lot or bundle has been ironed, said pad means including means whereby it may act as a carrier for lot or bundle identifying means and having a portion greater in thickness than usual flatwork whereby to be effective to actuate trip mechanism associated 90

or cooperating with the ironing machine and normally unaffected by flatwork of usual thickness. 95

4. A lot or bundle marker for use with flatwork ironing machines, said marker comprising pad means adapted to be passed through an ironing machine to indicate when a given lot or bundle has been ironed and having the corner portions of its forward edge in rounded form, said pad 100

means including means whereby it may act as a carrier for lot or bundle identifying means and having a portion greater in thickness than usual flatwork whereby to be effective to actuate trip mechanism associated with the ironing machine and normally unaffected by flatwork of usual thickness. 110
